CLAIM

The ornamental design for an outlet cover with LED assembly, as shown and described.

DESCRIPTION

FIG. 1 is a perspective view of an outlet cover with LED assembly showing my new design;
FIG. 2 is a front side view thereof;
FIG. 3 is a rear side view thereof;
FIG. 4 is a right side view thereof;
FIG. 5 is a left side view thereof;
FIG. 6 is a bottom plan view thereof; and,
FIG. 7 is a top plan view thereof.
